CLAIM

The ornamental design for a shotgun cartridge wad or similar article, as shown and described.

DESCRIPTION

FIG. 1 is a perspective view of a shotgun cartridge wad, or similar article, showing my new design;

FIG. 2 is a perspective view of the design from the opposite direction of FIG. 1.

FIG. 3 is a cross-sectional view of the design taken at section 3—3 of FIG. 5.

FIG. 4 is a cross-sectional view of the design taken at section 4—4 of FIG. 6.

FIG. 5 is a side elevational view, the opposite side being a mirror image thereof;

FIG. 6 is a front elevational view, the rear being a mirror image thereof; and

FIG. 7 is a top plan view thereof.

FIG. 1

FIG. 3

FIG. 4

FIG. 7

FIG. 5

FIG. 6
